UNITED STATES PATENT OFFICE.

GEORGE F. PAGE, OF CONCORD, NEW HAMPSHIRE.

MACHINE-BELTING.

SPECIFICATION forming part of Letters Patent No. 439,282, dated October 28, 1890.

Application filed July 7, 1890. Serial No. 357,994. (No model.)

To all whom it may concern:

Be it known that I, GEORGE F. PAGE, a citizen of the United States, residing at Concord, in the county of Merrimac and State of New Hampshire, have invented certain new and useful Improvements in Machine-Belting, of which the following is a full, clear, and exact description, reference being had to the accompanying drawings, making part of this specification, in which—

Figure 1 is a transverse vertical section of a piece of machine-belting constructed in accordance with my invention. Fig. 2 is a similar section of the same in place upon the face 15 or rim of the pulley, illustrating the manner in which it conforms by its lateral flexure to the "crowning" or transverse curvature of the same when in use. Fig. 3 is a transverse vertical section through a piece of my improved belting in which the outer layer of fabric is provided with a greater number of longitudinal hinge-joints than in the belt 20 shown in Fig. 1. Fig. 4 is a plan of a piece of my improved belting.

This invention relates particularly to an improvement on a belt composed of an inner layer or thickness of leather, or suitably-prepared rawhide, combined with an outer layer or thickness of fabric composed of a series of 25 independent longitudinal strips separated from each other on a line or lines parallel with the edges of the belt, for which Letters Patent of the United States, No. 400,005, were granted to me on the 19th day of March, 1889.

The object of my present invention is to produce a double belt having the same general character as that for which my aforesaid patent of March 19, 1889, was granted; but in which certain additional advantages are secured by varying the construction of the outer layer or thickness of fabric, as hereinafter particularly set forth.

In the said drawings, A represents my improved belt, which is composed of an inner layer or thickness *b* of leather or suitably-prepared rawhide, which forms the under or wearing surface which comes in contact with the pulleys, as set forth in my aforesaid patent. To this under layer or thickness *b* of 45 leather or rawhide, is secured, by cement, rivets, sewing, or in any other suitable manner, an outer layer or thickness *c* of knit or

woven fabric, which may be composed of cotton, linen, or other material suitable for the purpose. This layer or thickness *c* of fabric, 55 which is placed upon the outer side of the belt, instead of being composed of two or more parallel strips placed longitudinally of the belt and with their edges close together, as shown and described in my aforesaid patent, 60 consists of a single strip having one or more longitudinal grooves or flexible hinge-joints *d*, whereby sufficient lateral flexure of the belt is secured to enable it to readily conform to the crowning surface of the pulley over which 65 it may run, thus making complete contact therewith from side to side, as is desirable to secure the best results. These longitudinal hinge-joints *d* are preferably produced in the operation of weaving or knitting the fabric, 70 by leaving out or omitting one or more of the longitudinal or warp threads at the point or points where the hinge joint or joints occur, thus reducing the thickness of the fabric at the point or points where lateral flexure is de- 75 sired. Any other means or method may, however, be adopted in manufacturing the fabric which will produce therein one or more of the said longitudinal flexible joints.

The above-described belt, while it retains 80 the flexible longitudinal joint or joints in the outer layer or thickness, as in my aforesaid patent of 1889, has the additional advantage that the outer layer or thickness is composed of but a single strip of fabric, so that while 85 the belt is equally as flexible as that shown in my aforesaid patent it is nevertheless stronger, and the liability of the belt splitting along the line of the joint or joints is entirely avoided. Another advantage which I secure 90 is that there are only two edges to the outer layer of fabric instead of four or more. Hence there is much less necessity of fastening the two layers or thicknesses together by means other than cement, and there is also much less 95 liability of the fabric separating from the leather or prepared rawhide which forms the inner layer or thickness. I have also found in practice that there is a liability of a belt in which two or more separate strips of fabric 100 are used for an outer layer becoming crooked by reason of the strips not stretching uniformly; but where the outer layer is composed of a single strip of fabric provided with a lon-

itudinal joint or joints in accordance with my invention this difficulty is avoided.

The purposes or uses to which I propose to apply my improved belt, and the advantages derived from its use other than those above mentioned, are substantially the same as described in my aforesaid patent of 1889.

What I claim as my invention, and desire to secure by Letters Patent, is—

10 A driving-belt composed of a layer or thickness of leather or suitably-prepared rawhide, consisting of a single strip forming the inner

or wearing surface or portion, combined with an outer layer or thickness consisting of a strip of fabric which is provided in the weaving or knitting with one or more longitudinal flexible joints, substantially as and for the purpose described. 15

Witness my hand this 2d day of July, A. D. 1890.

GEORGE F. PAGE.

In presence of—

HARRY W. AIKEN,
R. HENRY MARSH.
